BY

William E. Richards
his ATTORNEY.

UNITED STATES PATENT OFFICE.

ISRAEL HOFFMAN, OF BROOKLYN, NEW YORK.

HAIR-WAVER.

1,380,064.

Specification of Letters Patent.

Patented May 31, 1921.

Application filed March 5, 1918. Serial No. 220,620.

To all whom it may concern:

Be it known that I, ISRAEL HOFFMAN, citizen of the United States, and resident of Brooklyn, in the county of Kings and State 5 of New York, have invented a certain new and useful Hair-Waver, of which the following is a specification.

This invention relates to toilet articles, and particularly to that class of articles 10 known as hair-wavers, and has for its object to produce such an article in a simple and economical manner and form, and at the same time so that it will be efficient in use.

15 A further object of my invention is to produce a hair-waver that may be applied to the hair with or without heating, and that will operatively remain in the hair until purposely removed, and that will produce 20 the form of waves commonly known as Marcel waves.

These and other objects of my invention are set forth in the following specification, and shown in the accompanying drawings, 25 which form a material part of this disclosure, and in which:—

Figure 1 is a perspective view of my improved hair-waver;

Fig. 2 is an enlarged end elevational view 30 thereof showing the same applied to the hair; and

Fig. 3 is a fragmental detail view, partly in section, showing the means employed for securing the clamp.

35 My improved waver consists of two principal parts or members, a female member 10, and a male member 11.

The female member 10 may be made from any desirable material and is preferably 40 constructed of a sheet metal plate formed into a plurality of longitudinally extending corrugations or undulations comprising semi-circular lower and upper portions 12 and 21 and vertical side walls 13. The male

45 member 11 is similarly formed, having semi-circular lower portions 14 projecting into the semi-circular portions 12 of the female member, and a semi-circular upper portion 4 which receives the semi-circular portion 50 21 of the female member, the convolutions of the male member being completed by the vertical side walls 3.

The members 10, 11, arranged as above described, are pivotally attached to each other

55 at one end of the waver, ears 15, 15 on the member 11, being secured to similar ears 16, 16, formed on the member 10, by means of eyelets 17.

The member 11 is also provided with another ear 22 for convenience in use when 60 opening the waver.

Attached to the free end of the member 10 by the eyelets 19, 19, is a swinging wire bail or clamp 18, which may be swung over the top of the member 11 when the latter is 65 in its closed position in the member 10, to compress and hold these parts together, as shown in Fig. 2, or which may be turned into the position shown in Fig. 1 when it is desired to open the waver. The different 70 corrugations are of such size as to cause the vertical side walls to be spaced apart when the device is in operative position, while the catch 18 acts to hold the male member in position with the semi-circular portions of 75 the corrugations spaced substantially evenly with the vertical side walls.

In operation, the waver, being in its opened position, may be introduced into the hair 20, or a desired amount of the latter may be 80 placed between the members 10, 11, which are then closed together so as to tightly compress and confine the hair held between them, and the clamp 18 then adjusted so as to hold the parts in their closed positions. 85 The clamp 18, when adjusted, holds the member 11 against swinging movement away from the member 10 when the vertical and semi-circular portions of the corrugations of the respective members are evenly 90 spaced apart. The hair may be left in the waver as long as necessary or desirable. By the employment of a number of these wavers, as much hair as desired may be simultaneously waved. 95

Having described my invention, what I claim as new and desire to secure by Letters Patent is:—

A hair waving device composed of two longitudinally channelled members, of sheet 100 metal, each having outer walls and straight line channelled bases, forming a plurality of transverse convolutions, the convolutions of one member being smaller than those of the other member that said members may interfit upon an interposed layer of hair to "wave" the latter, adjacent ends of said members being cut away to leave lugs ex- 105

tended from their outer walls, lugs on the smaller member being offset to meet the lugs on the larger member, pivots whereby the lugs of said members are engaged, the pivotally engaged relation of said members being such that their opposed channels are longitudinally spaced apart throughout when said members are closed upon the in-

terposed layer of hair, and engaging means for the free ends of said members. 10

Signed at New York city, in the county of New York and State of New York, this 4th day of March, A. D. 1918.

ISRAEL HOFFMAN.

Witness:

GEO. N. VERITZAN.
